Specification of Letters Patent. Patented June 27, 1922.

Application filed August 21, 1920. Serial No. 405,065.

To all whom it may concern:

Be it known that we, RODNEY H. YALE, PAUL W. HUTCHINS, citizens of the United States of America, and KARL MERTING, a citizen of Germany, all residents of Lincoln, Lancaster County, and State of Nebraska, have invented certain new and useful Improvements in and Relating to Windmills, of which the following is a specification.

10 This invention relates to certain improvements in windmills; and the objects and nature of the invention will be readily understood by those skilled in the art in the light of the following explanation of the accompanying drawings illustrating what we now believe to be the preferred mechanical expressions or embodiments of our invention from among other forms, constructions and arrangements within the spirit and scope 20 thereof.

An object of the invention is to so improve the working head of windmills as to render it possible to economically and successfully maintain the proper lubrication 25 of certain working parts with the end in view of producing a highly desirable so-called self oiling windmill.

Another object of the invention is to provide improvements in windmills of the back 30 geared and of internal geared type, with the end in view of attaining certain advantages and results over prior windmill gearings known to us.

Another object of the invention is to provide certain improvements in various features of windmill working heads with the ends in view of overcoming difficulties heretofore experienced and in attaining advantages over the prior art as known to us.

40 With these and other objects in view our invention consists in certain novel features in construction and in combinations and arrangements as more fully and particularly set forth and specified hereinafter.

45 Referring to the accompanying drawings:—

Fig. 1 shows in side elevation a windmill working head embodying the various features of our invention, the wind wheel 50 and regulator vane or tail being but partially illustrated, the wind wheel spider or

hub being partially shown in longitudinal section.

Fig. 2 is a side elevation, corresponding to Fig. 1, but showing the opposite side of 55 the head.

Fig. 3 is a rear elevation of the working head, the vane being broken away and the wind wheel not being shown.

Fig. 4 is a top plan view of the working 60 head, the vane being broken away, the wheel not being shown except for a portion of its hub which appears in horizontal longitudinal section.

Fig. 5 is a vertical section longitudinally 65 of the wind wheel shaft, approximately in the plane of the line 5—5, Fig. 4, showing the main frame or bracket partly in section and partially in side elevation, the main stem pipe being shown in elevation with a 70 portion broken away.

Fig. 6 is a detail top plan of the main frame casting, the main stem being shown in cross section, the windwheel shaft, gearing and journal box cap not being shown: 75

Fig. 7 is a detail elevation of the brake shoe:

Fig. 8 is a detail vertical section showing the internal gear and the gearing therein, 80

In the drawings, we do not show the tower or other support on which the head is mounted, nor do we show the mounting and supporting bearing for the head as the head can be supported and mounted in any suitable manner, as will be understood by those skilled in the art. 85

We do illustrate, however, the vertical main stem or pipe 1, which is alined or concentric with the vertical axis around 90 which the head rotates or swings. This stem forms a part of the main frame inasmuch as the main frame or bracket casting is rigidly clamped or otherwise secured to said stem to turn therewith. 95

Any suitable regulator vane or tail 3 is employed, although we do not illustrate the same in full, and this vane is coupled to the head through the medium of said stem which forms the vertical axis on which said 100 vane is horizontally swingable. To this end, the casting or yoke 2, of said vane is con-

fined to rotate on said stem in the usual or any other suitable manner.

As usual, the vertically reciprocating pump or other operating rod 4, depends and operates through the stem and extends upwardly therefrom where it works in the guide or slideway 5 clamped to the upper end of the stem and projecting upwardly therefrom.

10 The guide is longitudinally slotted or open at one side for the passage and vertical movement of the lateral pin or stud 8, fixed to said reciprocating rod and through the medium of which the rod is reciprocated by link or pitman 9. The upper end of the pitman is journaled on pin 8 while the lower end of the pitman receives the wrist or crank pin 10 of the crank 11. The crank 11 is driven by the windmill wheel (or main drive) shaft 12, as hereinafter set forth.

15 The complete windmill wheel of the solid type, is not shown but the hub thereof is illustrated fixed on the outer end of the shaft 12 and this hub comprises the rear hub section or spider 13.

20 In the particular embodiment illustrated, this spider is of the rearwardly extending conical type that overhangs the wheel shaft 12 and this hub comprises the rear hub section or spider 13.

25 In the particular embodiment illustrated, this spider is of the rearwardly extending conical type that overhangs the wheel shaft 12 and this hub comprises the rear hub section or spider 13.

30 The vane 3 is controlled by any suitable means to vary the angle of the vane with respect to the wind wheel axis and to throw the same into and from the wind, although in the particular embodiment illustrated, we show the usual weighted regulator lever 14 in this instance, fulcrumed on a fixed pin 15 projecting from the rear end of the main frame casting and connected to operate the vane through the medium of the usual gearing 16. This lever is raised by chain or other flexible pull connection 7, extending upwardly to pulley 6 arranged at the rear side of guide 5 and carried thereby. As usual the chain depends from the pulley 6 through the stem 1 and from thence to the means by which the chain is operated.

35 In the particular embodiment illustrated, the rear end of the main frame bracket or casting embodies a vertical sleeve or hub 18, through which the main stem 1 extends, and from the rear of which the rigid fulcrum pin 15 projects rearwardly. The vertical bore through this hub is sufficiently large with respect to the stem to permit the stem to slip into the hub in assembling and to more or less snugly fit opposite sides of the stem against relative lateral movement of the stem and hub with respect to the longitudinal axis of the wind wheel, while the bore is enlarged or elongated in the direction of the bore diameter aligned with said wheel axis to permit limited relative movement of the stem and hub in assembling, to enable the internal forwardly projecting radial stud or boss 19

to enter the radial socket or perforation 20 in the rear side of the stem. The hub is cast with this boss 19 projecting radially into the bore and the rear side of the bore is formed with inclined faces 21 diverging forwardly at opposite sides of the boss so that the boss is located centrally between said faces, thus forming a V jaw or seat to receive the rear side of the stem. When assembled with the hub, the stem is formed to this V seat and held rigidly in place with the boss 19 interlocking with the stem, by clamping blocks 22 radially movable in the bore and forced inwardly by radial clamping screws 23, having their heads accessible at the exterior of the front side of the hub. The hub is formed with internal sockets in which the blocks 22 are radially movable and into which the blocks can be withdrawn forwardly, to permit the stem to clear the boss 19 in entering and in withdrawal from the hub.

40 In assembling, when the boss 19 has entered the perforation 20, the screws 23 are adjusted rearwardly to tightly lock and wedge the hub and stem together against possibility of release of the boss from the perforation and against relative looseness. We do not wish to limit ourselves to the clamping blocks as the inner ends of the screws 23 might abut directly against the stem.

45 We have thus provided a most rigid, efficient and economical structure for rigidly securing the stem and main frame bracket together and for permitting convenient assembly of these parts as well as easy separation thereof, in case of need.

50 The hub 18 is an integral part of the main frame bracket casting, and the hub is located at the rear end of the horizontal forwardly extending radial arm 24 of this casting, said arm being preferably T shape in cross section and located in the vertical plane of the longitudinal axis of the wheel shaft and located below the rear portion of said shaft and below the gearing by which the crank 11 is driven from the wheel shaft. At the front end of the arm 24 the bracket casting extends upwardly to form a supporting upright or pedestal 25 for the wheel shaft journal boxing and the gearing and crank. The casting provides a longitudinally elongated horizontally projecting pillow 26, for the wheel shaft journal boxing and this pillow can be provided with suitable removable bearings 27 at the front and rear ends of the pillow.

55 We preferably provide a single elongated cap 28 for this pillow formed by a casting and this cap is bolted to the pillow in any usual or suitable manner and is preferably provided with end removable bearings 27 corresponding to the pillow bearings 27.

60 The bracket casting not only forms the arm 24, the upright 25 and the pillow 26, but

also provides a transverse vertical wall or plate 29 above arm 24 and at the rear of the upright 25. This plate or wall is approximately circular with its center approximately 5 alined with the wheel shaft axis so that the plate forms the rear face of the upright and extends radially upwardly and laterally from the center longitudinal axis of the pillow 26 and defines the rear end of said pillow. This 10 plate 29 is formed with a central opening for the passage of the wheel shaft 12 and this opening is extended vertically (see 29^a) through the top edge of the plate to permit the vertical movement of the wheel shaft to 15 and from the pillow 26 (when the cap 28 is detached) and also to receive the rear end of said cap 28 and permits its movement to and from the pillow when being applied and removed therefrom (Fig. 5).

20 A fixed large internal gear 30, concentric with the wheel shaft 12, is supported by, clamped to and arranged at the rear face of the wall 29. This internal gear is cup shaped or in the form of a circular vertical 25 wall or disk 30^a having a cylindrical forwardly projecting annular flange 30^b at the outer end portion of its inner surface forming the gear 30. The front edge of this flange 30^b fits the rear face of vertical wall 30, and the open side housing 30^a, 30^b is tightly (yet removably) clamped to the flange by stud bolts 30^c (or other suitable means) to provide a dust and grease proof box or housing for the gearing hereinafter 35 described. In this connection, it will be noted that we provide any suitable means for normally closing or sealing the vertical slot or opening 29^a. For instance, we show plate 29^c closing this slot and removably se- 40 cured to the cap 28 and to the box forming the internal gear 30, by machine screws 29^d. The end wall 30^e is formed with an opening and hollow boss 30^d alined with the wheel shaft and the longitudinal bore thus pro- 45 vided receives longitudinally removable bearing bushing 30^e which is concentric and of enlarged internal diameter with respect to the wheel shaft 12. This shaft extends from the pillow 26 and plate 29, through 50 the internal gear box and the bearing 30^e and projects rearwardly from said bearing into the vertical plane in which the crank 11 operates. This crank 11 is mounted on and keyed to the rearwardly projecting end 55 of a hollow shaft 33, concentric with shaft 12 and mounted in and carried by the bearing 30^e and arranged longitudinally of said shaft. The shaft 12 extends through the hollow shaft and is journaled therein to ro- 60 tate freely with respect thereto, and suitable gearing is provided whereby the shaft 12 drives the hollow shaft at a scaled speed with respect to the speed of shaft 12. For instance, a spur gear 34 is keyed or other- 65 wise fixed on the shaft 12 and located at the rear face of wall 29 and within and concentric with the relatively large internal gear 30. Two similar spur gear pinions 35 are arranged in constant mesh with both the large gear 30 and the small gear 34, and 70 these pinions are arranged diametrically opposite each other and eccentric with respect to the large and small gears and are interposed between the circumference of the small gear and the interior of the large gear. 75

The axes of the large and small gears and pinions are all parallel, and the pinions are mounted to rotate on studs 35^a projecting forwardly from, carried by and fixed to the opposite ends of a cross arm 35^b rigid with 80 the front end of the hollow shaft 33. The cross arm 35^b is arranged within the box formed by gear 30 and immediately to the rear of gear 34 and pinions 35.

The gear 34 is directly driven by the 85 wheel shaft and rotates the two diametrically opposite pinions on their respective axes 35^a as said pinions are in constant mesh with said gear. However, the two pinions are also in constant mesh with the 90 fixed internal gear 30, and consequently rotation of the pinions on their axes causes them to travel in an endless path within the internal gear and around gear 34, thereby rotating the cross arm through the medium of 95 the stud shafts 35^a and consequently driving the hollow shaft 33 to actuate the crank 11, at the desired scaled speed with respect to the rate of rotation of the wind wheel shaft. 100

We attain material advantages in windmill practice by the gearing approximately as disclosed wherein the driving power is taken from the main drive (wheel) shaft at diametrically opposite points thereof because so-called "side draft" is thereby 105 eliminated and uniform application of power and approximate uniform speed of the crank arm throughout its full circle of rotation are thereby attained and jerky 110 movements are avoided.

By employing the large fixed internal gear as a part of the reducing gearing, we are enabled to utilize said gear in providing a grease and dust proof chamber for the reducing gearing. The chamber formed by the internal gear and the back wall 29 of the bracket by which said gear is supported, can receive a large supply of grease in which the gearing 34, 35, 30, operates, and 115 this supply will be sufficient to last for a long period of time, and will also serve to lubricate the hollow shaft bearing within bushing 30^e, as well as the bearing of the main shaft within the hollow shaft. We 120 thus utilize parts of the gearing to form the grease chamber and avoid the necessity of employing a separate or additional encasement.

We also gain advantages in so-called 130

“back geared” windmills by arranging the working parts of the gearing so as to be balanced with respect to the wheel shaft axis which axis is radially arranged with respect to the longitudinal axis of the vertical stem 1. In other words, in a windmill of this type, we gain advantages by arranging the working parts of the gearing so as to operate concentrically with the main drive (wheel) shaft.

We also gain advantages in so arranging the parts of the gearing, that the large internal gear approximately carries the weight of the hollow shaft and attached parts through the medium of the substantial bearing bushing 30°, which bushing is readily renewable. Also, it will be noted that the hollow crank shaft has an elongated bearing on the main drive shaft as well as in the elongated large diameter bushing 30°, and that an elongated support and bushing for the rear end portion of said main shaft is also thereby provided. We also gain advantages by reason of the ease with which access can be gained to the main shaft and gears. By disconnecting the crank 11 from the pitman 9, and removing the stud bolts 30° and the upper machine screw 29^a, the internal gear 30, 30^b, 30^a can be slipped rearwardly on the main shaft end carrying the hollow shaft and the parts carried thereby so as to expose gear 34 and the interior of the hollow gear.

Furthermore, by removing the main shaft journal boxing cap 28, and the stud bolts 30°, and the lower machine screw 29^a (the crank being disconnected from the pitman) the main shaft can be lifted from its pillow, carrying the internal gear, pinions, and hollow shaft with it upwardly from the fixed back plate or wall 29.

Lubrication of the wind wheel shaft is provided for by grease box 40, in this instance, shown as an integral part of the cap 28, rising therefrom in advance of the back wall 29, and having its enlarged open bottom traversed by the shaft and open to the journal boxing between the bearings 27, 27^a. This box is equipped with a suitable removable cover and is designed to contain a supply of grease that will lubricate said shaft for a long period of time, all as set forth and claimed in the patent application of R. H. Yale, filed Feby. 13, 1920, Se. No. 358,386.

In this connection, it will be noted that the reducing gearing is lubricated by the grease in the hollow or internal gear and is not dependent for lubrication on flow of lubricant from the main shaft bearings, and on the other hand the journal boxings for the main shaft are not dependent for lubrication on spent grease from the gearing but are supplied from box 40. The crank wrist pin bearing in pitman 9, is lubricated by grease from grease box 42 on the pitman,

and the reciprocating rod bearings in guide 5 are lubricated from grease box 43 into which the rod projects and which is supported by said guide, all approximately as disclosed by and claimed in the said R. H. 70 Yale patent application.

We utilize the rear end face of the wheel spider or hub 13 as a braking surface by providing therein an annular (preferably) V-groove 44, to receive the V-rib 45 of a 75 brake shoe 46. This brake shoe is formed with a center hub or guide 47 slideable longitudinally on the approximately semi-cylindrical portion of the main shaft journal boxing between the wheel hub and the 80 bracket upright 25.

This brake shoe is formed with a depending arm 48, at its lower end having transverse vertical eye 49 loosely confined to reciprocation on the horizontal pin 50 parallel with the wheel shaft and projecting forwardly from the front end of bracket arm 24. If so desired, this pin can be removably secured in a socket in said arm.

The brake shoe is removed to and from 90 braking engagement with the wind wheel hub through the medium of a push rod 51 secured to the hub portion of the brake shoe and projecting rearwardly therefrom and pivotally joined to the upper end of an upright vertically-swingable lever 52 between its ends fulcrumed on horizontal pin 53 projecting laterally from and carried by the bracket upright 25.

This lever is operated to apply and release the brake shoe by horizontally disposed rearwardly extending link 54 at its front end, pivotally joined to the lower end of lever 53 and at its rear end suitably coupled to any desirable operating or controlling means for automatically applying and releasing the brake or for applying and releasing the brake by means manually operable from the ground or elsewhere.

In the particular example illustrated, we 110 show the yoke of the vane formed rigid with approximately radially projecting bumper arms 60, 60', arranged approximately at an angle of ninety degrees to each other, to strike the main frame bracket when the 115 vane is in operative position and when the vane is at its limit of inoperative position, respectively, and thus establish the limits of relative movement between the vane and main frame.

If so desired, the operative connection between the brake shoe and the vane can be established through the medium of a vertical stud or pin 55 located a suitable radial distance from the main stem and carried by one 125 of the bumper arms. We show a pull rod 54^a, at its rear end pivotally confined to this pin and at its front portion operatively connected to link 54. The link 54, in this instance, is in the form of a longitudinally 130

hollow housing or a tube, with the rod 54^a extending and slidably longitudinally therein and extending slidably through a perforation in the rear end wall of the tube or 5 housing 54. A stop nut 54^c is longitudinally adjustable on the front end of the pull rod 54^a within the housing. A coiled spring 54^d is loosely arranged on the rod 54^a within the housing and seated at one end against the 10 rear end wall of the housing while the rear end of the spring is normally located a substantial distance from the end nut 54^c. A stop pin 54^b is carried by the pull rod at the exterior of the housing and in normal engagement with the rear end of the housing. The arrangement is such that when the vane is in operative position, the stop pin 54^b engaging the housing 54 will hold the brake shoe from operative position. When the 15 vane swings from operative position the pull rod 54^a will be drawn rearwardly until its nut 54^c strikes spring 54^d whereupon continued movement of the vane will cause application of the brake through the medium 20 of the spring, housing 54, and the lever and link as before described. When the vane is swung back to operative position, the pull rod 54^a will slide forward freely with respect to the housing until the pin or stop 54^b 25 strikes the rear end of the housing, whereupon the continued movement of the vane will cause release of the brake.

It will thus be noted that the vane has a certain amount of independent swing so far 30 as the brake shoe is concerned, and this is of peculiar advantage in windmill practice. For instance, we usually arrange the brake operating connections to allow the vane an approximate free swing of forty five degrees. 40 The brake shoe and its hub are of the annular mutilated type, the brake shoe is not a complete annulus, but a radial opening or passage 45^a permits lateral removal of the brake shoe from the main shaft journal boxing, or removal of the boxing cap and the 45 main shaft without disturbing the brake shoe.

The bearings of the brake shoe guides 47, 49 on the journal boxing and on the pin 50 hold the brake to rectilinear reciprocation 50 in a path parallel to the main shaft axis, and serve to support and guide the brake shoe. The pin 50 can be removable to permit convenient removal and application of the 55 brake shoe from the main shaft journal boxing.

It is evident that various changes, modifications and variations might be resorted to, that various features might be omitted, that 60 constructions might be added, all without departing from the spirit and scope of our invention and hence we do not wish to limit ourselves to the exact disclosures hereof.

What we claim is:—

65 1. In a windmill head, in combination, a

main shaft, a wind wheel in fixed driving relation to said shaft for actuating the same, a driven shaft, and reducing gearing in constant fixed operative relation with respect to said shafts for driving the driven shaft 70 from the main shaft continuously at a fixed ratio during rotation of the windwheel, said gearing embodying an internal gear, a center pinion, and pinions in mesh with and interposed between the center pinion and 75 said gear for balancing the gearing tooth pressures, said gear and pinions being in constant fixed operative relation with said shafts, means being provided enclosing said gearing in a grease-tight grease chamber. 80

2. In a windmill head, in combination; a main shaft; a windwheel in constant driving relation to said shaft; and power transmission mechanism, from said shaft, constructed and arranged to perform work at a point 85 below said head, said mechanism embodying a driven shaft, and reducing gearing in constant fixed operative connection with both of said shafts for driving the driven shaft from the main shaft continuously at a fixed ratio 90 during rotation of the main shaft, said gearing including a relatively large internal gear and cooperating gearing within the same, means being provided in cooperation with said internal gear to form a grease- 95 tight lubricant chamber enclosing said reducing gearing.

3. A windmill comprising, in combination, a main drive shaft, a crank shaft concentric therewith, and gearing for driving the crank 100 shaft from the drive shaft embodying a fixed internal gear concentric with said shafts and gearing rotated by the drive shaft and in constant mesh with the internal gear, means being provided cooperating with said gear to 105 enclose said gearing in a grease tight chamber.

4. In windmill gearing, a main drive shaft, a windwheel on the front end of said shaft, a windmill frame having a journal box 110 for and supporting said shaft, a driven shaft concentric therewith, and gearing for rotating the driven shaft from the drive shaft, said gearing having axes alined and parallel with said shafts and embodying pinions arranged diametrically opposite each other with respect to said shafts, said pinions being in constant driven relation to said drive shaft, said journal box being located between the windwheel, and said driven shaft 115 and gearing.

5. In a windmill, in combination, a main stem, a windwheel shaft radially arranged with respect to said stem, a driven shaft having its axis alined with that of said wheel 125 shaft, and gearing for rotating the driven shaft from the wheel shaft, said gearing being balanced with respect to the wheel shaft axis and embodying gearing elements having their axes either alined or parallel with the 130

wheel shaft and a driving pinion fixed on and in constant driven relation to said wheel shaft.

6. In a windmill, in combination, a main stem, a wind wheel shaft radially arranged with respect to said stem, a support for said shaft embodying removable bearings, a driven shaft having its axis alined with that of said wheel shaft, and gearing for rotating the driven shaft from the wheel shaft, means providing a tight lubricant chamber enclosing said gearing, said gearing being balanced with respect to the wheel shaft axis and embodying gearing elements having their axes either alined or parallel with the wheel shaft.

7. In a windmill, in combination, a main stem, a windwheel shaft radially arranged with respect to said stem, a hollow driven shaft having its axis alined with that of said wheel shaft, and gearing for rotating the driven shaft from the wheel shaft, said gearing being balanced with respect to the wheel shaft axis and embodying gearing elements in constant driven relation to said wheel shaft and having their axes either alined or parallel with the wheel shaft.

8. A windmill comprising, in combination, a hollow driven shaft having a cross arm provided, at its opposite ends, with pinions mounted to rotate independently and having axes parallel with said shaft, a windwheel shaft having its axis alined with that of the driven shaft, and gearing actuated by and in constant driven relation to the wheel shaft for causing said pinions to travel in an annular path concentric with the wheel shaft and to thereby rotate the driven shaft through the medium of said cross head.

40 9. A windmill comprising, in combination, a driven shaft having a cross arm provided, at its opposite ends, with pinions mounted to rotate independently and having axes parallel with said shaft, a windwheel shaft; a wind mill head providing supporting boxes and removable bearings for said shafts; a windwheel on the front end of the wheel shaft in advance of said boxes, bearings and driven shaft; and gearing arranged 45 in rear of said wheel shaft box and bearings and in constant driven relation to said wheel shaft for causing said pinions to travel in an annular path concentric with the wheel shaft and to thereby rotate the driven shaft 50 through the medium of said cross head, said gearing embodying a gear fixed to the wheel shaft, and a fixed concentric internal gear, said pinions being interposed between and in constant mesh with said gear and internal 55 gear.

60 10. A windmill comprising, in combination, a main drive shaft, a hollow shaft receiving the same and rotatable thereon, and gearing for driving the hollow shaft from the drive shaft, and embodying a fixed in-

ternal gear concentric with the main shaft and having a hub providing a bearing for the hollow shaft.

11. A windmill comprising, in combination, a main drive shaft, a crank shaft concentric therewith, and gearing for driving the crank shaft from the drive shaft embodying a fixed internal gear concentric with said shafts and gearing rotated by the drive shaft and in constant mesh with the internal gear, said internal gear having a closed end wall provided with a hub providing a bearing for said crank shaft, means being provided cooperating with said internal gear in forming a grease tight chamber enclosing 75 said gearing for maintaining constant long continued lubrication thereof.

12. A windmill comprising, in combination, the wind wheel shaft, a driven shaft concentric therewith, and gearing for rotating the driven shaft from the wheel shaft and in constant driven relation to the wheel shaft, said gearing having axes alined and parallel with said shafts and embodying pinions arranged diametrically opposite each other with respect to said shafts, said pinions being eccentrically arranged with respect to said shafts and traveling in an annular path concentric therewith and being carried by and driving said driven shaft.

13. In a windmill, in combination, a main stem, a wind shaft radially arranged with respect to said stem, a driven shaft having its axis alined with that of said wheel shaft, and gearing for rotating the driven shaft from the wheel shaft, said gearing being balanced with respect to the wheel shaft axis and embodying gearing elements having their axes either alined or parallel with the wheel shaft, said gearing embodying a 95 large fixed internal gear having a closed end wall with a hub providing a supporting and journal bearing for said driven shaft, said driven shaft extending to the exterior of 100 said hub for connection to perform work.

14. A windmill comprising, in combination, a windwheel shaft constituting the main drive shaft, a hollow shaft receiving the same and rotatable thereon, and gearing for driving the hollow shaft from the drive shaft said hollow shaft provided with an exterior crank for connection to drive mechanism to perform work.

15. A windmill comprising, in combination, a windwheel shaft constituting the main drive shaft, a hollow shaft receiving the same and rotatable thereon, and gearing for driving the hollow shaft from the drive shaft, said gearing embodying a fixed internal gear closed to form a grease chamber 115 enclosing said gearing and providing a supporting bearing for said hollow shaft, said hollow shaft projecting to the exterior of 120 said chamber and provided with means for transmitting power to perform work.

16. In a windmill, in combination, a main frame swingable about a vertical axis, a wind wheel shaft carried by said frame radially with respect to said axis and provided 5 with a gear, a hollow driven shaft on and concentric with said shaft and provided with power transmitting means for connection to perform work, said hollow shaft provided with axes parallel with said shafts and 10 carrying rotary pinions in constant mesh with diametrically-opposite portions of said gear and rotated on their axes thereby, and means for causing said pinions to travel in an annular path around said gear and to 15 thereby rotate said hollow shaft.
17. In a windmill head, in combination, a supporting frame having a vertical stem, a wind wheel shaft mounted in said frame, said frame providing a vertical transverse 20 wall, and power transmission mechanism from said shaft for connection with means to perform work below said head, said mechanism embodying a rotary crank, and reducing gearing for driving said crank 25 from said shaft, said gearing including an internal gear having an open side and a closed side, and a driving pinion within and geared to said internal gear, said wall closing the open side of said gear and cooperat- 30 ing with the gear to form a grease tight lubricant chamber.
18. In a windmill head, in combination, a supporting frame, a main shaft, a rotary crank, and reducing gearing for driving the 35 crank from the shaft, said gearing embodying a relatively-large internal gear, and a driving pinion within the same and geared thereto, said shaft provided with a wind-wheel at one end, said frame provided with 40 separable bearings for said shaft, said bearings being arranged between said gear and said wheel, said shaft being vertically removable from said frame and bearings, said gear being open at one side and closed at 45 the other, said open side of said gear being closed to provide a lubricant chamber within said gear.
19. In combination, in a windmill head, a frame providing a fixed transverse wall, and 50 wheel shaft bearings, a wheel shaft mounted therein and extending through said wall, an internal gear having an end wall and hub, said gear secured to and supported by said wall to form a closed grease chamber, a driven shaft mounted in said hub, and gearing 55 within said grease chamber for driving the driven shaft from the wheel shaft, said driven shaft having power transmitting means at the exterior of said chamber for 60 connection to perform work.
20. In a windmill head, in combination, a main frame embodying a bracket providing journal boxing for the wind wheel shaft and a fixed vertical transverse back wall, a 65 windwheel shaft mounted in said boxing and removable vertically therefrom and projecting rearwardly through said wall, said wall formed with a vertical slot for the removal and replacement of said shaft, a vertical open side housing removably secured to said 70 wall and having its open side closed thereby to form a grease chamber, said housing having a bearing, a driven shaft in said bearing and alined with the wheel shaft, and gearing in said chamber for driving the driven 75 shaft from the wheel shaft.
21. In a windmill, a frame, a wind wheel shaft mounted therein, a vertical transversely arranged open side housing removably secured against said frame and closed 80 thereby to form a grease chamber, said housing providing a large internal fixed gear concentric with said shaft and a bearing opening alined therewith, a hollow rotary shaft mounted in said opening and sup- 85 ported by said housing and at the exterior thereof having power transmitting means, said wheel shaft extending through said chamber and into said hollow shaft and provided with a gear within said chamber, said 90 hollow shaft provided with radial arms for rotating the same, rotary pinions carried by said arms and in constant mesh with both said gear and said internal gear, said arms and pinions arranged within said chamber. 95
22. In a windmill, in combination, a vertical main stem, a reciprocating rod, a pitman for reciprocating the same, a bracket extending radially from the stem and having a hub receiving the same and fixed thereto, said bracket embodying a radial arm at its outer end having an upright providing a vertical transverse back plate or wall above the arm and a forwardly extending pillow for the wheel shaft radial with respect to 100 said stem, a wheel shaft in said pillow and extending rearwardly through and beyond said wall, means on said pillow to provide journal boxings for said shaft, a vertical transverse open side housing at the rear of 105 said wall and removably clamped thereto to form a gear box and grease chamber, a crank shaft mounted in and carried by said housing and provided with a crank at the rear thereof to actuate said pitman, and gearing 110 in said housing to drive the crank shaft from the wheel shaft.
23. In a windmill, in combination, a main stem having a radial socket, a main frame bracket having a hub to receive said stem and having an internal rigid projection to enter said socket, the bore of said hub being formed to permit relative movement between the hub and stem when assembling for entrance of the projection into the socket, and 115 clamping means to lock the hub and stem together against such movement.
24. In combination, in a windmill, a horizontally swingable windmill head bracket, a windwheel shaft mounted therein, and a 120
- 65
- 125
- 130

vertical main stem for said bracket and normally fixed thereto, said bracket having a vertical bore longitudinally receiving said stem, said bore being radially elongated with respect to said stem to permit relative lateral movement of the stem and bracket when assembling and disassembling, said bracket and stem formed to interlock against relative movement longitudinally of the stem 5 when moved laterally in one direction and to unlock when moved laterally in the opposite direction, exteriorly accessible means being provided for normally locking the bracket and stem together against said relative unlocking lateral movement.

25. In combination, in a windmill, a horizontally swingable windmill head bracket, a windwheel shaft mounted therein, and a vertical main stem for said bracket and 20 normally fixed thereto, said bracket having a vertical bore longitudinally receiving said stem, said bore being radially elongated with respect to said stem to permit relative lateral movement of the stem and bracket when assembling and disassembling, said bracket 25 and stem formed with a complementary locking projection and socket, said bracket being provided with adjustable clamping blocks and exteriorly accessible clamping 30 screws controlling the relative lateral movements of the bracket and stem.

26. In a windmill head, in combination, a bracket, a windwheel shaft carried by said bracket, and a cylindrical vertical main stem 35 for said bracket, said bracket formed with a vertical bore through which said stem extends, the bracket and stem being relatively movable longitudinally of the stem in assembling and disassembling, said bore being 40 laterally elongated to permit relative lateral movement of the bracket and stem, said bore at one side forming a V-jaw to grip the stem, the bracket at the other side of the bore having adjustable clamping means to 45 engage the stem and force the same into said jaw, means being provided to lock the stem and bracket together against relative movement longitudinally of the stem when the stem is forced laterally into said jaw.

50. 27. In combination, a windmill head bracket, a vertical tubular main stem for the head, the bracket having a vertical bore receiving the stem, the bore and stem being relatively formed to permit relative lateral 55 movement of the stem and bracket, the bore at one side formed to wedge and center the stem, the bracket and stem having an interlocking socket and projection, and adjustable clamping means accessible at the exterior of the bracket for forcing the stem 60 and bracket into and normally holding the same in interlocking relation.

28. In a windmill, in combination, a main drive shaft, a frame therefor rotatable on 65 a vertical axis, and power transmission

mechanism from said shaft arranged to perform work below said frame and embodying a depending operating connection alined with said axis, said mechanism comprising reducing gearing wherein the gear tooth pressures are balanced or equalized, said gearing being center driven with respect to said shaft, said frame provided with an accessible bearing box for said drive shaft arranged between the windwheel and said 75 transmission mechanism.

29. In a windmill, in combination, a main drive shaft, a frame therefor rotatable on a vertical axis, and power transmission mechanism from said shaft arranged to perform work below said frame and embodying a depending operating connection alined with said axis, said mechanism comprising reducing gearing wherein the gear tooth pressures are balanced or equalized, said 80 gearing being center driven with respect to said shaft, and in constant operative connection with said shaft at a fixed ratio, and means providing a grease-retaining gear box enclosing said gearing. 90

30. In a windmill, a center-drive geared-back power transmission mechanism from the windwheel to a point below the windmill head for there performing work, said mechanism embodying multiple gears enclosed in a grease chamber and including an internal gear forming the major portion of the walls of said chamber. 95

31. In a windmill, a center-drive geared-back power transmission mechanism embodying multiple gears wherein the gear tooth pressures are equalized, said gears including an internal gear, and a pinion fixed on and constantly driven by the windwheel shaft. 100

32. In a windmill, a center-drive geared-back power transmission mechanism embodying multiple gears wherein the gear tooth pressures are equalized, said gears including an internal gear, and means whereby said gears are enclosed in a grease chamber within and formed in part by said internal gear. 110

33. In a windmill, a center-drive geared-back power transmission mechanism embodying multiple gears between the main drive shaft and the driven shaft in fixed operative connection with the drive shaft to constantly drive the driven shaft at a fixed ratio, several of said gears having axes parallel with each other and with the driven shaft, said multiple gears being arranged to equalize the tooth pressures with respect to said driven shaft, in combination with the supporting frame of the windmill head 120 providing removable bearing boxings for said shafts. 125

34. In a windmill, a geared-back power transmission mechanism embodying multiple gears, and means providing a closed 130

grease chamber for said gears, said gears including a large gear forming the major portion of the walls of said chamber.

35. In a windmill, a geared-back power transmission mechanism embodying multiple gears, and means providing a closed grease chamber for said gears, said gears including a large gear forming a part of the enclosing walls of said chamber.
- 10 36. In a windmill, a geared-back center-drive power transmission mechanism embodying an internal gear, in combination with the supporting frame of the windmill head, and means cooperating with said gear 15 to provide a closed chamber for retaining a supply of grease for continuous lubrication of said mechanism.

37. In a windmill, in combination with the windwheel and its shaft, and the supporting frame of the windmill head, a geared-back center-drive power transmission mechanism embodying an internal gear, and a mechanism-driving pinion on and in constant driven relation to the wheel shaft 25 and in constant driving relation in said mechanism, said internal gear being fixed.

38. In a windmill, a power transmission mechanism embodying multiple gears including an internal gear, means co-operating with said internal gear to provide a closed grease chamber for said multiple gears, in combination with the windwheel and its shaft, and the supporting frame of the windmill head.

35 39. In a windmill, in combination, the supporting frame of the windmill head, the windwheel and its shaft constituting a drive shaft, a driven shaft alined therewith, and an interposed gear assembly operatively 40 connecting said shafts, means being provided whereby said gear assembly is enclosed in a grease chamber, capable of retaining a large supply of lubricant in contact with said assembly.

45 40. In combination, in a windmill, the supporting frame of the windmill head, a windwheel, a main driving element in constant driven relation to said wheel, a driven element, and an interposed assembly of 50 meshing gears operatively connecting said elements in constant driving relation, and embodying several gears having their axes parallel with said driving element and several gears having their axes alined with 55 that of said element, whereby a center drive power transmission is provided wherein gear tooth pressures are equalized.

41. In combination, in a windmill, the supporting frame of the windmill head, a 60 windwheel, a main driving element in constant driven relation to said wheel, a driven element, and an assembly of meshing gears operatively connecting said elements in constant driving relation and embodying a 65 center driving gear, a gear alined there-

with, and several oppositely rotating gears each in mesh with both first mentioned gears and arranged to travel in an annular path concentric with the common axis of the first mentioned gears.

70 42. In combination, in a windmill, the supporting frame of the windmill head, a windwheel, a main driving element in constant driven relation to said wheel, a driven element, and an assembly of meshing gears 75 operatively connecting said elements in constant driving relation and embodying a center driving gear, a gear alined therewith, and several oppositely rotating gears each in mesh with both first mentioned gears and 80 arranged to travel in an annular path concentric with the common axis of the first mentioned gears, and means whereby all of said gears are enclosed in a grease chamber.

43. In combination, in a windmill, the 85 supporting frame of the windmill head, a windwheel and its shaft constituting a rotary driving element, a rotary driven element alined therewith, and an assembly of meshing gears operatively connecting said 90 elements and embodying a center gear in constant driven relation to said shaft and several gears in mesh therewith and arranged oppositely with respect to each other and said center gear, for the production of a 95 center-drive balanced power transmission mechanism.

44. In a windmill, in combination, the supporting frame of the windmill head, a windwheel, a main drive shaft driven thereby, a drive pinion fixed on said drive shaft, a reciprocating rod, gearing for driving said rod from the said drive pinion, said gearing working on two or more sides of said drive pinion while driving said rod and in 105 constant driven relation to said pinion, said frame providing exterior journal boxing for said shaft.

45. In a windmill, in combination, a windwheel, the supporting frame of the windmill head, an internal gear, means removably fixing said gear to said frame, said gear being closed to form a tight lubricant retaining chamber, a main drive shaft, a drive pinion on said drive shaft centered in said 110 internal gear, gearing connecting said drive pinion with said internal gear, a reciprocating rod driven by said drive pinion through the medium of said connecting gearing and internal gear.

115 46. In a windmill, in combination, a windwheel, the windwheel shaft, means providing accessible bearing boxing for said shaft, an internal gear and a drive pinion within said internal gear, with connections 120 for driving the windmill pump rod, and means for closing said internal gear for holding a supply of lubricant therein.

47. In combination, in a windmill, the supporting frame of the windmill head, a 130

windwheel, said frame providing removable top bearing boxing for the center drive shaft, an internal gear, a center drive shaft driven by said wheel, carrying a drive pinion within the internal gear, in its center, connecting gearing between said drive pinion and internal gear, set to equalize working pressure on the cogs of said drive pinion.

48. In a windmill, in combination, a windmill head bracket, a wind wheel shaft, said bracket provided with a separable journal boxing for said shaft, said bracket constructed and arranged to render the shaft vertically removable from the bracket, and 10 power transmission mechanism from said shaft arranged for connection to perform work below the head, and including an internal gear and connected gearing within said gear and embodying a gear box enclosing 15 said gearing and arranged on the shaft end 20 beyond said separable boxing.

49. In a windmill, in combination; a windmill head bracket horizontally rotatable about a vertical axis; a wind wheel shaft 25 radially arranged with respect to said axis and carried by said bracket, a pinion keyed to said shaft, a crank rotating on an axis aligned with said shaft and arranged for connection to perform work below said head 30 bracket, and gearing in fixed constant operative connection with the pinion and crank to continuously drive the crank at a fixed ratio during rotation of the shaft, said gearing being oppositely arranged and balanced 35 with respect to said pinion, said pinion being centrally arranged within said gearing to balance tooth pressures throughout each complete revolution of the crank.

50. In a windmill, in combination, a windmill head bracket, a wind wheel shaft 40 carried thereby, a pinion keyed on said shaft, a rotary crank for connection to perform work below the head, and gearing from the pinion to the crank for driving 45 the same including a relatively large internal gear, said pinion being located within and having operative connection with said internal gear, said internal gear being closed at the sides and rim to form a tight lubricant 50 box formed to receive a charge of lubricant

for long continued lubrication of the pinion and gearing.

51. In a windmill, in combination, a windmill head bracket, a wind wheel shaft journaled therein, a pinion keyed on said shaft intermediate the shaft length, a relatively short hollow shaft rotatable on the rear end of the wheel shaft and provided with a crank for connection to perform work, a support providing an exterior bearing for 60 said hollow shaft, and gearing for driving said hollow shaft from said pinion.

52. In combination, in a windmill, a wind wheel shaft, a windmill head bracket carrying said shaft, a separate vertical tubular 65 main stem for said bracket, said bracket formed with a vertical bore receiving said stem, and accessible means for detachably securing the bracket and stem together in assembled position.

70 53. In combination, in a windmill, a bracket, a wind wheel carried thereby and having an annular braking surface, the bracket provided with a guide pin spaced laterally from the wheel axis, an open segmental brake shoe adapted to said surface and formed with a rigid projecting guide and supporting arm, said arm having an eye loosely receiving said guide pin, and means for applying and releasing said brake 75 shoe.

54. In a windmill head, in combination, a bracket, a wind wheel shaft, said bracket provided with a separable journal boxing for said shaft, a vane, a windwheel having a 85 braking surface, an open segmental brake shoe adapted to said surface and partially surrounding said boxing and formed with a lateral guiding and controlling arm 90 loosely engaging and guided by a part carried by the bracket, and a lost motion operating connection from the vane to said brake shoe embodying a spring, a vertical lever fulcrumed to and arranged beside the bracket, link connections, and an adjustable stop.
